HAROLD B. SMITH, OF WORCESTER, MASSACHUSETTS, ASSIGNOR TO WESTINGHOUSE ELECTRIC & MANUFACTURING COMPANY, A CORPORATION OF PENNSYLVANIA

ARC-GAP DEVICE

Application filed September 8, 1925. Serial No. 55,193.

My invention relates to arc-gap devices and particularly to arc-gap voltage measuring terminals for high-voltage circuits.

One object of my invention is to provide simple and economical substitutes for sphere-gap terminals, and particularly for relatively large high-voltage terminals of spherical form which are expensive and difficult to construct to the required degree of accuracy.

10 Another object of my invention is to provide an arc-gap terminal device that may readily be provided for circuits of voltages of such relatively high values that the provision of the usual sphere-gap terminals therefor is impracticable, if not impossible.

It has been usual, in voltage-testing practice, to employ spaced conducting spheres or members having hemi-spherical adjacent conducting surfaces.

20 To ensure accurate operation and consistent results, such devices must necessarily be of very accurate formation, a slight deviation from the true spherical form disturbing the electrostatic field and causing results 25 which may or may not bear any regular mathematical relation to each other for different voltages and arcing distances.

With the increase of commercial voltages, testing devices of this character become increasingly important and the provision of suitable arcing terminals particularly for very high voltage measurements has already become a troublesome problem.

It is my aim to overcome the difficulties 35 attending the provision and use of sphere-gap terminals for high-voltage circuits and to provide a device that shall not only be readily adaptable for voltages of all values but that shall be extremely simple in construction and economical to manufacture.

Accordingly, in practicing my invention, I provide paired conducting terminals having portions of such simple geometrical contour and other portions of such relatively 45 small size as to render the same relatively easy to construct to the required degree of precision.

Figure 1 of the accompanying drawings, is a side elevational view of a portion of a 50 voltage-measuring device embodying a pair

of arcing terminals constructed and related in accordance with my invention,

Fig. 2 is a plan view of the members shown in Fig. 1, and

Fig. 3 is an enlarged detail side view, partially in section and partially in elevation, of one of the members shown in the other figures, illustrating one form of construction thereof.

The device comprises, in general, a pair 60 of terminal members embodying intermediate portions 1, end portions 2 and conducting leads or supports 3 that are connected to the intermediate portions 1 and to a suitable framework or other supporting structure (not shown).

The intermediate portions 1 are preferably of cylindrical form having true circular cross-sectional area and being of relatively great length compared to the diameters thereof. These portions, while preferably constructed of relatively thin sheet metal, such as copper, may also be constructed and supported by insulating or other structural, or metallic material covered with metal foil or 75 very thin metal or otherwise provided with conducting surfaces.

The portions 1 are preferably disposed with the longitudinal axes thereof in right-angular relation in spaced parallel planes, although 80 they may be disposed in other relations and may be mounted for adjustable relative movement in any suitable manner.

The portions 1 may further be of partially cylindrical, instead of full cylindrical form, 85 with the outer curved surface of each constituting the next adjacent portion to the other, as if the outer longitudinal half, or other than half, of each, as shown in the drawing, were removed and the leads 3 connected to the remaining or adjacent portions. In such modified form, a consideration would be that no change should be permitted in the symmetry or localized degree of concentration of the field sufficient to cause the ultimate arc to 95 travel between other than substantially the nearest points on the portions 1. This result may be insured, as by rounding the farthest edges of the members or by placing conducting shields adjacent thereto. Attend- 100

ing conditions, such as electric field distributions, and concentrations, temperature, humidity and wind velocity, of course affect the measurement, as with the usual sphere gaps.

5 The end portions 2, which may be omitted if the mid portions 1 are sufficiently long in consideration of the voltages to be used, are provided to permit the mid portions to be of practical lengths and, where the outer surfaces of the ends are of substantially spherical curvature of the same radius as the mid portions, the latter may be of minimum lengths.

10 As shown in Fig. 3, the end portions 2 are of hemi-spherical form having cylindrical shoulders 4 fitted into the ends of the mid portion 1. The conducting lead and support 3 is also of suitable diameter to prevent concentration of the field thereon and is preferably connected to the mid portion 1 by a member 5 disposed therein as shown, or through mechanical support to the interior structural framework supporting the thin outer cylindrical conducting surface.

15 The cylindrical form of the mid portions 1 renders them very easy to manufacture of thin sheet metal or other suitable material and the end portions 2, since they are removed from the ultimate arcing surfaces of the members 1, need not be of the same size 20 nor of the same degree of accuracy as sphere-gap members for the same voltages. That is, they need not be of accurately turned and polished metal, but may be made by a tinsmith of thin sheet metal or other suitable 25 material.

30 While I have shown and described a particular form of my invention, changes may be effected therein without departing from the spirit and scope thereof, as set forth in the 35 appended claims.

40 I claim as my invention:—

1. An arc-gap device comprising a pair of elongated terminal members disposed in angular spaced relation and having adjacent 45 conducting surfaces of substantially cylindrical curvature free of field-disturbing portions within the zone of effective field operation between said members.

50 2. An arc-gap device comprising a pair of elongated terminal members disposed in angular spaced relation having adjacent conducting surfaces of substantially cylindrical curvature and rounded ends to prevent field disturbance in the zone of effective field operation between said members.

55 3. An arc-gap device comprising a pair of elongated terminal members disposed in spaced substantially right-angular parallel-plane relation and having adjacent conducting surfaces of substantially cylindrical curvature free of field-disturbing portions within the zone of effective field operation between said members.

60 4. An arc-gap device comprising a pair of elongated terminal members disposed in

spaced substantially right-angular parallel-plane relation having adjacent conducting surfaces of substantially cylindrical curvature merging into surfaces of substantially spheroidal curvature at the ends thereof.

65 In testimony whereof, I have hereunto subscribed my name this seventeenth day of August, 1925.

HAROLD B. SMITH.
